DEFROSTER FOR REFRIGERATORS

Alonzo W. Ruff, York, Pa., assignor to York Ice
Machinery Corporation, York, Pa., a corpora-
tion of Delaware

Application September 3, 1930, Serial No. 479,542

25 Claims. (Cl. 62—115)

The present invention relates to defrosting evaporators, and more particularly to smaller types of evaporators such as are used in connection with refrigerator cabinets for butchers, 5 grocers and restaurants. The problem of defrosting evaporators in small installations presents serious difficulties in that the evaporators are small and the evaporation of refrigerant therein is sluggish. Various means have been 10 proposed heretofore for introducing external heat to the refrigerated space, all of which are objectionable because the refrigerator is heated up unnecessarily and is out of use for long periods of time and also because inexperienced 15 operators often heat up the evaporator to such an extent that excessive pressures occur. It is likewise impracticable to apply the "hot gas" method of defrosting to small refrigerators having only one or two evaporators connected to 20 the suction of the compressor in series, there being no evaporation and consequently no gas discharge from the compressor for use in the evaporator. In fact, it is desirable to defrost the evaporators of small installations when the 25 compressor is closed down so that no high pressure gas is available.

It has been found that the application of heat to the evaporator itself by means of an electric heating element defrosts the evaporator coil 30 evenly and quickly without appreciably heating up the refrigerator cabinet or rendering it useless during the defrosting period.

It has further been determined that an electric heater submerged in the refrigerant evaporates the refrigerant quickly and the gas thus given off condenses in the evaporator, the heat evolved by condensation melting the frost. This can be accomplished in a relatively 35 short length of time and as a consequence little 40 rise in temperature results therefrom.

The present invention provides for heating the evaporator by an electric heating element, preferably a coil submerged in the refrigerant and adjacent the bottom of the evaporator. Control 45 devices responsive to temperature changes in the refrigerant and to pressures in the discharge and suction lines of the compressor are associated with the motor and heating element to connect and disconnect the motor or heater when cer- 50 tain predetermined conditions exist.

The invention will be understood from the following description taken in connection with the accompanying drawings, in which

55 Figure 1 is a diagrammatic illustration of one form of the present system, the motor and sev-

eral controls being shown and a refrigerating cabinet having therein an evaporator provided with an electric heating element disposed in the lower header of the evaporator.

Fig. 2 is an elevation of a modified arrangement of evaporator and heating element, the latter being wound on the lowest coil of the evaporators; and

Fig. 3 is another modification of the invention in which the heating element is disposed in the leg of the suction trap.

Referring to the drawings, the refrigerating system comprises the usual compressor 11 driven by a motor 12, the condenser 13 and evaporator coil 14. The system illustrated is one of the "flooded" type and includes a suction trap 15 as well as a float chamber 16. In practice, the evaporator comprises several coils 14 arranged in parallel relation between an upper or gas header 17 and a lower or liquid header 18, the latter being in communication with the suction trap through a leg 19 and having an oil drain 21.

The compressor motor receives its current from a source of electric energy designated 22 from which the heating element 23 is also supplied with current. A switch 24 permits the operator to connect either the motor or the heater with a power line circuit or to open the circuit entirely. Interposed between the source of current and switch 24 is an excess pressure switch 25 responsive to pressure in the discharge line 26 of a compressor and adapted to open the circuit to stop the compressor when a predetermined pressure in the discharge line has been built up. A similar excess pressure switch 27 is connected with the suction line 28 of the compressor, this switch responding to pressures resulting from evaporation of the refrigerant during application of heat thereto and interdrupting the heater circuit when a predetermined pressure in the evaporator has been attained.

It will be understood, of course, that the compressor is inoperative while the heating circuit is closed. Still another control device comprises a thermostatic switch 29 mounted within the refrigerator cabinet 31 and in series with the motor 12. The thermostatic switch is set for high and low limits, thereby to control operation of the compressor and maintain the proper temperature in cabinet 31.

If desired, an automatic by-pass valve 32 may be employed as a further measure of safety, the valve being designed to respond to pressures above those for which safety switch 25 is intended to respond.

When it is desired to defrost the evaporator coils the switch 24 is thrown over to close the heater circuit. The refrigerant in the evaporator is thus heated by the heating element 23 submerged in the refrigerant within the lower header of the evaporator. The position of the heater, above the lower end of the leg 19 and at or near the bottom of the evaporator coil, is such that the vapors evolved by heating the 5 liquid refrigerant are constrained to flow through the evaporator toward the suction trap and in so doing are condensed within the coil. The heat resulting from condensation in turn melts the frost on the coil. At the same time the liquefied refrigerant flows by gravity to the bottom of the evaporator in a more or less heated condition, the temperature and corresponding pressure being relatively high during the defrosting period. Uniform distribution of heat over all 10 parts of the evaporator in a relatively short period is thus obtained.

In the modification shown in Fig. 2 the heating element comprises a winding surrounding the lowest coil of the evaporator. Heat is transmitted to the refrigerant through the coil causing circulation of the refrigerant by the resulting evolution of gas in the coil. Defrosting is accomplished in much the same manner as that described with respect to Fig. 1.

30 Fig. 3 illustrates still another arrangement wherein the heating element lies within the leg 19 connecting the suction trap with the liquid header 18. In this form of the invention the refrigerant is constantly warmed and circulated 35 through the coil to melt the ice formed on the exterior of the coil.

While several forms of the invention have been illustrated and described herein, it is not intended that the specified arrangements limit the invention to what has been shown in the drawings.

40 What is claimed is:—

1. In a refrigeration system, an evaporator; a defroster for said evaporator comprising means for applying heat to a portion of said evaporator; and means responsive to a predetermined pressure in said evaporator for interrupting the application of heat thereto.

2. In a refrigeration system, an evaporator; a defroster for said evaporator comprising means for applying heat to the lowermost portion of said evaporator; and means responsive to a predetermined pressure in said evaporator for interrupting the application of heat thereto.

3. In a refrigeration system, an evaporator; a defroster for said evaporator comprising an electric circuit; an electric heating means in said circuit for applying heat to a portion of said evaporator; and means responsive to a predetermined pressure in said evaporator for interrupting said circuit.

4. In a refrigeration system, an evaporator; a defroster for said evaporator comprising an electric circuit; an electric heating means in said circuit for applying heat to the lowermost portion of said evaporator; and means responsive to a predetermined pressure in said evaporator for interrupting said circuit.

5. In a refrigeration system, an evaporator; a defroster for said evaporator comprising means within the evaporator and submerged in the refrigerant for applying heat to the refrigerant.

6. In a refrigeration system, an evaporator; a defroster for said evaporator comprising electric heating means within the evaporator and sub-

merged in the refrigerant for applying heat to the refrigerant.

7. In a refrigeration system, an evaporator; a defroster for said evaporator comprising means within the evaporator and submerged in the refrigerant for applying heat to the refrigerant; and means responsive to a predetermined pressure in said evaporator for interrupting the application of heat thereto.

8. In a refrigeration system, an evaporator; a defroster for said evaporator comprising an electric circuit; an electric heating element in said circuit and submerged in the refrigerant for applying heat to the refrigerant; and means responsive to a predetermined pressure in said evaporator for interrupting said circuit.

9. In a refrigeration system, an evaporator having upper and lower headers; a defroster for said evaporator comprising means within the lower header and submerged in the refrigerant for applying heat to the refrigerant.

10. In a refrigeration system, an evaporator having upper and lower headers; a defroster for said evaporator comprising means within the lower header and submerged in the refrigerant for applying heat to the refrigerant.

11. In a refrigeration system, an evaporator having upper and lower headers; a suction trap; means for connecting said headers with the suction trap; and means within one of said connections and submerged in the refrigerant for applying heat to the refrigerant.

12. In a refrigeration system, an evaporator coil; and a defroster for said coil comprising an electric heating element surrounding and in contact with the lowermost portion of said coil for applying heat thereto.

13. In a refrigeration system, an evaporator having liquid and gas headers; a conduit forming a communicating passage between said headers and spaced from the evaporator; and a defroster comprising heat applying means in said passage.

14. In a refrigeration system, an evaporator having liquid and gas headers; a suction trap having a connection with each of said headers; a defroster for said evaporator comprising heat applying means in the connection between the liquid header and said suction trap for heating liquid refrigerant, said heat applying means being so disposed in said connection that vapors resulting from application of heat are constrained to flow through the evaporator.

15. The method of defrosting the evaporator of a refrigeration circuit connected to liquid and gas headers which comprises applying heat to liquid refrigerant locally and within the liquid header.

16. The method of defrosting the evaporator of a refrigeration circuit having supply and suction connections with a compressor which comprises suspending the flow of the refrigerant through the evaporator and applying heat directly to the refrigerant internally of and near the lowermost portions of the evaporator.

17. The method of defrosting the evaporator of a refrigeration circuit which comprises generating heat within the volatile refrigerant in the evaporator to vaporize a portion of the refrigerant, while retaining substantially all the refrigerant in the evaporator.

18. The method of defrosting the evaporator of a refrigeration circuit which comprises applying heat locally to volatile liquid refrigerant in the evaporator at substantially the lowest point in the evaporator to vaporize the refrigerant, while retaining substantially all the refrigerant in the evaporator. 5
19. The method of defrosting the evaporator of a refrigeration circuit which comprises suspending the flow of refrigerant through the circuit and applying heat directly to the refrigerant internally of and near the lowermost portion of the evaporator. 10
20. In a refrigeration system, an evaporator; and a defroster for said evaporator comprising an electric heating element contacting the lowermost portion of said evaporator for applying heat thereto. 15
21. A refrigeration system including a compressor and an evaporator; an electric motor for driving said compressor; a defroster for said evaporator comprising an electric heating element; and means for selectively energizing the motor and the heating element. 20
22. A refrigeration circuit including an evaporator and means for circulating refrigerant through the circuit; an electrical circuit includ- ing means therein for operating said circulating means; a defroster comprising a second electrical circuit having a heating element therein; and means for selectively closing said circuits. 5
23. A refrigeration circuit including an evaporator and means for circulating refrigerant through the circuit; means for heating said evaporator to defrost the same; and means for selectively actuating the circulating means and the heating means. 10
24. In a refrigeration system, an evaporator containing volatile refrigerant; a defroster for said evaporator comprising means for applying heat locally to the refrigerant; and means responsive to a predetermined physical change of the refrigerant in the evaporator for interrupting the application of heat thereto. 15
25. In a refrigeration system, an evaporator containing volatile refrigerant; a defroster for said evaporator comprising an electric circuit; an electric heating means in said circuit for applying heat locally to the refrigerant; and means responsive to a predetermined physical change of the refrigerant in the evaporator for interrupting the application of heat thereto. 20
